DIVIDER AND RACK CONSTRUCTION

Henry B. Goodman, New London, Conn.

Application September 19, 1955, Serial No. 535,021

3 Claims. (Cl. 211—184)

The present invention relates to a rack or shelving structure particularly adapted to hold magazines and books. It is an object of the present invention to provide a rack structure having a unique shelving arrangement in which individual shelves forming the magazine rack may be adjustably divided to accommodate books, magazines, or the like, of various sizes.

Another object of the present invention is to provide a magazine rack structure of unique and simple design utilizing an extruded aluminum section formed in such a manner as to make the assembly process simple in nature.

Another object of the present invention is to provide a partitioning member for shelves in a rack in which the partitioning member is secured into position by spring tensioning action of the member between opposite walls of the shelf on which it is positioned.

Another object of the present invention is to provide partitioning members for shelves which may readily be moved longitudinally along the shelf or removed entirely from it, but which when inserted in position will not accidentally be loosened or moved from their set position.

These and other objects of the present invention will be more clearly understood when considered in connection with the accompanying drawings in which:

Figure 1 is a cross-sectional elevational view of the magazine rack, and

Figure 2 is a cross-sectional plan view taken substantially along the line 2—2 of Figure 1 with the supporting legs of the rack not shown.

As illustrated in the drawings, the rack is formed of a rear wall 1 which may be of any suitable material such as Masonite. The rear wall 1 may be supported by U-shaped tubular leg members 2 having cross braces or support platforms 3 and 4. Platform 4 extends forward and has forward platform section 4a and sides 30. Secured by screws 31 or other suitable means to the platform is the channel member 32 having a recess to receive the base of the rear wall 1. The rack is prevented from slipping sideways by the sides of the legs 2 which bear against the surface 7a. Side wall members 5 and 6, each having a pair of longitudinally extending recesses 7 and 8, are positioned at either longitudinal edge of the rear wall 1 with the rear wall 1 positioned in the recesses or channels 7. If desired, the side wall members may be provided with a suitable decorative design such as illustrated in cross section in Figure 2. Secured to the back and side walls is at least one shelf generally indicated as 9. This shelf is formed preferably of a single piece of extruded aluminum and has a cross section providing the bottom leg 10 and forward leg 11. The bottom leg 10 is formed with a longitudinally extending channel member 12 having the open length of the channel aligned with the rear edge of this bottom leg 10. A second channel member 13 is also formed on the bottom leg 10 but towards its forward edge with the open length of the channel 13 facing downwardly. These channels have openings of uniform width which are designated

2

to receive and secure the shanks of self-threading screws. Thus, the shelf 9 is secured to the rear wall by the self-threading screw 14 which projects through the rear wall 1 into the channel member 12. Several such screws may be provided to rigidly secure the shelf in place. As the shelf 9 extends to the side walls 5 and 6, screws 15 may be provided which project through the side walls 5 and 6 and engage the side walls of the channel 13. A retaining bar 16 is provided for each shelf to prevent magazines from falling forward out of the shelf. This retaining bar 16 is preferably extruded of aluminum material and is formed of a single piece of material. This retaining bar has a thickness sufficient to permit its ends to engage the slots 8 in the side walls 5 and 6 and is secured in position by screws 17 projecting through the side walls 5 and 6 into a slot 18 formed in the extrusion process, the slot 18 being of sufficient width to engage the sides of the self-cutting screws 17.

In order to provide separate sections on a single shelf to receive different material which may vary in size, an adjustable pocket divider generally indicated at 19 is provided. This pocket divider is formed of a single piece of resilient material preferably spring steel and comprises a top section 20, rear section 21, bottom section 22 and forward section 23, with these sections all being continuous from the top to the forward section. The sections are also positioned and shaped to conform generally with the contour of the inside cross section of the shelf and rear wall as is illustrated. The forward section 23 and the top section 20 are separated from one another with the forward section 23 extending only partially up the forward leg 11 of the shelf 9. The top section 20 extends beyond the forward leg 11 of the shelf 9 and is provided with an engaging lip or bent section 24 which is shaped to engage the bead 25 formed at the top edge of the forward leg 11. This spring steel divider is initially formed with its forward section 23 normally inclined further forward as indicated by the divider illustrated at 19. When this divider, however, is positioned on the pocket 9, the forward section 23 is necessarily bent rearwardly to permit it to be inserted within the pocket. This bending of the forward section 23 causes a tension to be produced between the forward section 23 and the bent or lip section 24. This tension cooperating with the retaining action of the rear wall 1 secures the divider in position and prevents it from slipping longitudinally or out of the shelf when accidentally touched or moved. The dividers, however, may be moved by an individual if the top section 20 is pulled forward to reduce the tension between the forward and rear walls and permit the bent section 24 to be disengaged from the lip 25. When this bent section 24 is disengaged from the bead 25, the divider may then readily be removed and replaced in another position.

Having now described my invention, I claim:

1. In combination with a shelf structure having rear, front and bottom walls and open at its top, a divider made of a single strip of resilient material and having a top section which engages the front surface of the front wall of the shelf, rear and bottom sections which are a continuation of the top section and lying against the front and upper surfaces of the rear and bottom walls respectively, and a front section extending at substantially right angles from the front of the bottom section causing the top section to bear against the front surface of the front wall with said front section in pressing contact with the inner surface of the front wall.
2. In combination with a shelf structure having rear, front and bottom walls and open at its top, a divider made of a single strip of resilient material and having continuous top, rear, bottom and front sections, said bottom section being substantially the same width as the bottom wall and lying on the bottom wall, said front

and rear sections extending upwardly from the front and rear ends of the bottom section and diverging upwardly and pressing outwardly against said front and rear walls respectively, and a lip formed on the front end of the top section and engaging the front surface of the front wall and urged against the front surface of the front wall when the front and rear sections of the divider are compressed between the front and rear walls of the shelf structure.

3. In combination with a shelf structure having substantially parallel front and rear walls and a bottom wall, a divider to separate portions of the shelf and made of a resilient material comprising a bottom section resting on and extending from the rear to the front of the bottom wall, upwardly extending front and rear sections diverging from the front and rear ends of the bottom section and compressed between the front and rear walls of the

shelf structure, a top section extending forwardly from the top end of the rear section and terminating beyond the front wall, and means forming a continuation of the top section engaging the front surface of the front wall 5 of the shelf structure when the front and rear sections of the divider are compressed between the front and rear walls of the shelf structure.
